SPLICING MACHINES

William H. Giles, Brooklyn, N.Y., assignor to Nu Roll Corp., Mineola, N.Y., a corporation of New York
Filed Sept. 14, 1962, Ser. No. 223,714
3 Claims. (Cl. 242—58.4)

This invention relates to splicing machines having a pair of supply rolls and means for splicing the web from a fresh supply roll to the trailing end of the web from an exhausted supply web.

In machines of this character the web is pulled through the splicing machine by feed rolls which feed the web into a machine where it is to be used, such as a wrapping machine.

When the web from the reserve supply roll is to be spliced to the trailing end of the exhausted web the reserve web must be pulled into the splicer at a high rate of speed to match the speed of the exhausted web. This places a shock load on the reserve web and if the paper in the web does not have sufficient tensile strength to withstand the pull, the paper will be torn. An example of such paper is cigarette paper.

This invention has for its salient object to provide a splicing machine with supplementary or booster driving or feeding means eliminating the shock load as the splice is made by positively driving the paper supply roll from which the paper web is being withdrawn and fed through the splicing machine to a wrapping machine.

Another object of the invention is to provide means for controlling the tension on the web being fed, eliminating the need for a brake or other tension control device.

Another object of the invention is to provide a supply roll drive of the character described and control mechanism for automatically moving the drive for a fresh supply into operation when the paper on the alternative or other supply roll is exhausted.

Further objects of the invention will appear from the following specification taken in connection with the drawings which form a part of this application, and in which—

FIG. 1 is an elevational view, somewhat diagrammatic, and with parts omitted for the sake of clearness, of a machine embodying the invention;

FIG. 2 is an elevational view, partly in section, taken substantially on line 2—2 of FIG. 3, looking in the direction of the arrows, this view showing the left hand portion of the machine shown in FIG. 1;

FIG. 2A is an elevational view showing the right hand portion of the machine shown in FIG. 1, this view being an elevation of the portion of the machine shown in FIG. 3A;

FIG. 3 is a top plan view of the portion of the machine shown in FIG. 2;

FIG. 3A is a top plan view of the portion of the machine shown in FIG. 2A, parts being omitted.

FIG. 4 is a sectional elevation of the central portion of the machine, showing particularly the control mechanism for the right hand paper feeding mechanism;

FIG. 5 is a detail elevational view, partly in section, showing the driving connections between the central or primary feed rolls and the paper feed driving mechanism at the left of the center, this view showing the solenoid control for these driving connections;

FIG. 6 is a sectional elevation on an enlarged scale taken substantially on line 6—6 of FIG. 4, looking in the direction of the arrows; and

FIG. 7 is an enlarged detail elevational view of the primary feed rolls showing the webs in the position taken when they are being spliced.

The invention, briefly described, consists of a splicing machine having primary and secondary web feeding rolls, each web having secondary feeding rolls so controlled that

2

when one of the webs is exhausted the secondary feeding rolls for the other web will be automatically set into operation to feed the fresh supply web into a position in which it is spliced to the trailing end of the exhausted supply web.

The invention further comprises means under the control of detector means movable into frictional engagement with the fresh supply roll to drive said supply roll when the web from the other supply roll has become exhausted.

Further details of the invention will appear from the following description.

The splicing mechanism particularly illustrated in the drawings is mounted in a frame comprising a pair of side walls 10 and 11 supported by suitable pedestals 12 and 13. Each of the walls 10 and 11 has extending upwardly therefrom a bracket 14, and between the two upwardly extending brackets are mounted a pair of web supply rolls 15 and 16 which are freely rotatable upon spindles 17 and 18. The webs from the supply rolls 15 and 16 are designated 20 and 21.

There are two sets of web feeding rolls, one for each of the webs. The web is fed from the splicing machine by feed rolls 22 and 23 which feed the web to a wrapping machine or other machine in which it is to be used. The web is withdrawn from the splicing machine by the feed rolls 22 and 23 through a pair of primary feed rolls 24 and 25 which receive the web from secondary feeding rolls, one set of secondary feed rolls being provided for each of the webs. Since both sets of secondary feed rolls are exactly alike and are similarly controlled in their operation, the right hand set, viewing FIG. 4, will be described and designated by reference characters, and the left hand set, which is shown in FIG. 2, will be designated by the same reference characters primed.

Referring particularly to FIGS. 2A and 4, the right hand auxiliary feeding mechanism comprises a pair of feed rolls 30 and 31. The feed roll 31 is mounted between the side frames 10 and 11 and the feed roll 30 is mounted between a pair of arms 32 and 33 which are pivoted on a stud 34. The arms 32 and 33 have extending downwardly therefrom, brackets 35 and 35, in which are mounted rolls 36 and 37. There are also rolls 38 and 39 which are mounted between side frame members 55 and 56, and are in staggered relation with respect to the rolls 36 and 37. Side frame members 55 and 56 are mounted on and carried by a transverse bracket 57.

The web being fed passes first around an idler 40, over an idler 41 and a second idler 42, and thence between a pair of rolls 43 and 44. The rolls 43 and 44 when in their normal position, as shown in FIG. 2A, receive the web therebetween, but these rolls are formed of separated sections, as shown particularly in FIG. 6, the sections on the roll 44 being designated 49. The 55 roll sections are so spaced that they can intermesh so that the sections 48 will be disposed between the sections 49 at their peripheries, as shown in FIG. 4. This takes place when the web passing through the rolls 43 and 44, which may be termed detector rolls, is exhausted. The roll 44 is mounted on a bracket 50 pivoted on a spindle 51 which carries the idler roll 42. The bracket 50 can swing on its pivot and is swung in a clockwise direction by a spring actuated switch blade 52 which carries a roller 53, which in turn engages the downwardly extending end 54 of the bracket 50.

Under normal operation, as above described, the web from the roll 16 will pass between the detector rolls 43 and 44, but when this web is exhausted the roll 49 will be forced to the left, or in a clockwise direction, by the spring actuated switch blade 52, thus setting into operation control mechanism which will now be described.

When the paper web is passing between the rolls 43

and 44, the switch blade 52 will be in a position to hold the switch controlled thereby open. However, when the switch blade moves to the left, this movement being permitted after the exhausted end has passed between the detector rolls 43 and 44, the circuit through the switch is closed. When this happens, the solenoid 60' which controls the feeding operation of the web 20 and the supply roll 15 will be energized, viewing FIG. 2. It will be noted from FIGS. 2 and 5 that a roller 61' mounted on a pivoted arm 62' contacts the primary feed roll 24 and is driven thereby. When the solenoid 60' is energized a plunger 63' will be pulled upwardly, viewing FIG. 2. The plunger extends downwardly through an opening in a link 64', which is mounted on a fixed pivot 65' and is connected by a pin and slot connection 66' to the end of the arm 62'. A spring 67' is mounted on the lower end of the plunger 63' and is held in position by a nut 68'.

The roller 61' is normally held in the position shown in FIG. 2 by a spring 69'. When the solenoid 60' is energized, the plunger will be pulled upwardly, thus moving the arm 62' in a clockwise direction and moving the roller 61' into engagement with the auxiliary feed roll 31', thus driving the auxiliary feed rolls 30' and 31' and feeding the fresh supply web 20 to the primary feed rolls 24 and 25. This fresh supply web has on the free end thereof a tape T which connects the supply web 20 to the trailing end of the web 21 when these webs pass between the primary feed rolls 24 and 25, as shown in FIG. 7.

The pivoted arms 32 and 33 can be swung upwardly about the pivot 34 by means of a rod 70, this rod being spring actuated so that the end thereof will rest on the top of one of the side frame members when the arms are swung upwardly, as shown in dotted lines in FIG. 2. The arms are normally held in their lower position by means of a spring 71 which encircles the pivot shaft 34, as shown in FIG. 6, and engages the bracket which carries the arms.

In order to provide driving means for positively driving the web supply rolls, thus relieving tension of the web therefrom, supplemental driving connections under the control of detector rolls 43 and 44 and 43' and 44' are provided and this is shown particularly in FIGS. 2 and 2A.

As shown in FIG. 1, the shaft of the driving roll 23 has mounted thereon a sprocket 75 which drives a chain 76, which in turn has a sprocket 77 driven by the chain 76. Sprocket 77 is mounted on a shaft 78 and between the sprocket 77 and the shaft 78 there is an overrunning clutch 79. The shaft 78 has also mounted thereon a pulley 80 which, through a timing belt 81, drives a pulley 82 on the shaft 83 on which is mounted the feed roll 25. The shaft 83 has also mounted thereon a spur gear 84 which meshes with a spur gear 85 on the shaft 86 on which is mounted the feed roll 24.

Referring to FIG. 2A, it will be seen that the shaft 83 has also mounted thereon a pulley 87 which drives a belt 88, which in turn drives a pulley 89 mounted on a shaft 90. The shaft 90 is disposed between the frame members 10 and 11 and carries a pair of arms 91 between which is mounted a pulley 92. A second pulley 93 is mounted on the shaft 90 between the arms, and a belt 94 is driven by the pulley 93 and encircles the pulley 92.

The arms 91 are adapted to swing about the shaft 90 as an axis and are actuated to swing upwardly by a spring 95, shown in FIGS. 2 and 2A. The arms and the belt 94 carried thereby are normally held in their lower position by a latch 100 which engages a pin 101 disposed between the arms. The latch is pivoted at 102 and extends below the pivot, the lower end being connected to a link 103, the other end of which is connected to a plunger 104 of a solenoid 105. The solenoids 105 and 105' are adapted to be actuated by the closing of the

switch by the switch blades 52 and 52', which in turn are controlled by the detector means 43, 44 or 43', 44'. As these detector rolls move into intermeshing relation, the switch blades 52 and 52' controlled thereby close the switches. When the switches are closed, the solenoids 60 and 105 or 60' and 105' are energized and the switch 60 or 60' causes the rollers 61 or 61' to move into driving engagement with the feed roll 31 or 31'. The closing of the switches also energizes the solenoids 105 or 105', causing the solenoids to release the latches 100 and 100', permitting the spring 95 or 95' to swing the driving belt 94 or 94' upwardly into driving engagement with the supply roll. Springs 106 and 106' are connected to the lower ends of the latches 100 and 100' and normally close the latches.

The feed rolls 22 and 23 which pull the web into the wrapping or other machine are connected in the manner above described by the belt 76 and through an overrunning clutch to drive the shaft 78. The chain 76 is driven at a slightly lower speed than the peripheral speed of the rolls 22 and 23. This difference in speeds, however, is taken care of by the overrunning clutch. The drive from the shaft 78 to the shaft 83 will rotate the shaft 83 to drive the primary feed rolls 24 and 25 at a peripheral speed equal to or slightly faster than the peripheral speed of the belt 81. This difference in speed is compensated for by mounting the primary feed rolls 24 and 25 in slightly spaced relation so that the web can be pulled through this space and can pass freely, but when the condition shown in FIG. 7 pertains or, in other words, the position in which the splicing between the rolls 23 and 24 takes place, the rolls will put pressure on the tape, thus pressing the webs into close contact and accomplishing the splice.

In addition to overcoming the shock load caused by the force necessary to turn the reserve supply roll when the new web is spliced to the exhausted web, the supplementary or booster drive of the supply roll prevents the roll from gaining momentum and over traveling the speed of the pull or web feed rolls.

Such speeding up of the supply roll takes place after the reserve supply roll has been brought up to the speed of the exhausted web.

The positive belt drive of the reserve supply roll prevents this over traveling of the new web or prevents the roll from unrolling the web faster than it can be taken up or fed by the feed rolls.

Because of the fact that it is generally extremely difficult to match two separate driving speeds exactly, the supplemental or booster drive described above has two separate features which tend to act as differential agents to overcome this matched speed problem.

The first differential agent is built into the drive pulley of the supplemental or booster drive belt by inserting an overrunning clutch into the booster drive pulley. This belt is driven at a calculated speed which is purposely lower than the speed which the wrapping machine is pulling the web into the machine. This actually is supplying a drive which will bring the new supply roll up to 99% of its running speed, thus eliminating the start-up shock load on the web. As soon as the new supply roll starts to turn at full speed it is actually going faster than the driving belt which is resting on the periphery of the roll. This means that before the supply roll can over travel it must also over drive the drive belt. The force necessary to cause the drive belt to overdrive is always acting against the turning supply roll, thus preventing the supply roll from building up enough momentum to allow it over travel.

Moreover, the supplemental or booster drive allows instant start ups at full speed during the run of a supply roll, if the machine is stopped for one reason or another. Normally with thin web material the machine must be brought up to speed very gradually or there is danger of tearing the web due to an excess start-up shock load.

The second speed differential agent designed into this application is the design of the main squeeze roll. In this application there is no spring loaded roll to squeeze the splice, but instead, two rolls spaced one web thickness apart. These rolls are driven at a calculated peripheral speed equal to 99% of the actual running speed of the web, controlled by the wrapping machine. This lower running speed causes the travelling web to slip through these rolls as the material passes through them. With this system an overlap splice is employed and what actually happens is that the two thicknesses of material plus the thickness of the two faced pressure sensitive tape are actually forced through the one thickness opening, thus causing the necessary squeeze to perform the splice.

It will be noted particularly from FIG. 1 that the arms 91 which carry the driving belt 94 have secured thereto and extending outwardly therefrom, a post 110 having a knob or handle 111 at the outer end thereof. This post rests in a slot 112 in the side frame member 11 when the arms are in their lower position in which they are normally latched.

In order to sever the trailing end of the web 21, a knife 115 is pivotally mounted at 116 and is held in retracted position by a spring 117. The knife can be swung upwardly by a handle 118 which extends through the side frame member 11.

When the web is threaded through the feeding mechanism, the arms 70 or 70' are lifted to the dot and dash position shown in FIG. 2. It will be noted that when the arms are lowered the web is led around the rolls 37, 39, 36 and 38, in an undulating path. This gives added strength to the web, thus enabling it to withstand the tension due to the pull thereon. Also, as explained above, the supplementary drive on the supply rolls relieves the tension on the web.

Summary of operation

Assuming that the trailing end of the web 21 has passed through the detector rolls 43 and 44, as shown in FIG. 4, the switch blade 52 will close the switch and energize the solenoid 105' shown in FIG. 2, thus releasing the latch 100' and permitting the driving belt 94' to frictionally engage the supply roll 15 and rotate the roll. At the same time the solenoid 60' will be energized, thus lifting the feed roller 61' into engagement with the auxiliary feed roll 31' and initiating the downward feeding movement of the web 20. The frictional driving engagement between the feed belt 94' and the feed roll 15 will relieve tension on the web 20.

45
50

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. In a splicing machine, a pair of web supply rolls, 10 web feeding rolls for feeding a web from the splicing machine, web feeding means in the splicing machine for feeding a web from each supply roll, selective driving connections between said web feeding rolls and each of said web feeding means in the splicing machine, detector means for actuating the driving connections for the web from one supply roll when the web from the other supply roll is exhausted, independent driving means for each supply roll operatively driven by said web feeding rolls, and means controlled by said detector means for moving said independent roll driving means into operative roll driving position.
2. In a splicing machine, a pair of web feeding rolls, a pair of web supply rolls, separate feeding means for feeding the web from each web supply roll to said web feeding rolls, each of said separate feeding means comprising a fixed frame and a pivoted frame, detector means at one end of the pivoted frame, feeding rolls at the other end of the pivoted frame, one feeding roll being mounted on the pivoted frame and one roll being mounted on the fixed frame, and offset means on the fixed frame and on the pivoted frame for guiding the web in an undulating path.
3. In a splicing machine, a pair of web supply rolls, web feeding means for feeding a web from each supply roll, detector means for activating the feeding means for the web from one supply roll when the web from the other supply roll is exhausted, and means connected to the web feeding means for engaging and rotating a supply roll at a slightly slower speed than the speed of the web feeding means when the means for feeding the web from said roll is activated.
